UNITED STATES PATENT OFFICE.

LOUIS W. GREVE, OF CLEVELAND, OHIO, ASSIGNOR OF ONE-HALF TO THE CLEVELAND PNEUMATIC TOOL COMPANY AND ONE-HALF TO THE CLEVELAND ROCK DRILL COMPANY, BOTH OF CLEVELAND, OHIO, AND BOTH CORPORATIONS OF OHIO.

LIVE-AIR-ACTUATED SLEEVE VALVE FOR TOOLS.

Application filed February 15, 1923. Serial No. 619,142.

My invention relates to a novel construction of a live air actuated, sleeve valve adapted for use in a pneumatic hammer, rock drill or similar hammering implement and comprises a novel construction of a valve block, valve cap, valve and co-acting cylinder and piston, whereby a very compact and efficient structure is produced, the valve being actuated in both its forward and rearward directions by direct live air pressure, whereby a positive and accurate movement is imparted to the valve and the latter is held against its seat in its extreme positions without fluttering, for the proper period prior to shifting.

It further consists of a novel construction of a live air actuated, hollow sleeve valve adapted to have its piston pass through it during its rearward stroke, and a novel construction of co-acting ports and passages common to said valve and the co-acting piston, whereby the reciprocations thereof are controlled.

It further consists of a novel construction of a hollow valve, a co-acting piston and their adjuncts for effecting the admission and exhaust of the motive fluid at the proper periods.

It further consists of a novel construction of a hollow, live air actuated, sleeve valve, through which the piston passes on its rear stroke, said valve being shifted in both directions by direct live air pressure, in contradistinction to tools, wherein the valve is shifted in one direction by air compressed between the piston and valve.

It further consists of a novel construction of a constantly open live air passage, communicating with a pick-off port, and having a port leading to a live air pocket, constantly supplied with live air adapted, in conjunction with live air acting on the forward face of the valve, to shift the valve rearwardly, when the piston, in making its forward or down stroke, moves forwardly out of the valve.

It further consists in conjunction with my novel live air actuated sleeve valve and its adjuncts, of novel means controlled by the

piston for exhausting the forward end of the piston chamber.

It further consists of other novel features of construction and advantage, all as will be hereinafter fully set forth.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a longitudinal sectional view of a live air actuated sleeve valve and its adjuncts and a pneumatic hammering implement to which the same is applicable, the piston being shown as about to begin its return stroke and the valve being seated in its extreme rear position.

Figure 2 represents a section on the line 2-2 of Fig. 1 showing the constantly open live air admission port, the kick-off port and the port which leads constant live air pressure to the live air pocket or shoulder of the valve, whereby the same is shifted rearwardly.

Figure 3 represents on an enlarged scale a sectional view similar to Fig. 1 but showing the piston and valve in a position opposite to that shown in Fig. 1, the piston being in its extreme rear position, and the valve having shifted to its extreme forward position.

Figure 4 represents a transverse section on line 4-4 Fig. 1.

Figure 5 represents a perspective view of the live air actuated, sleeve, valve in detached position.

Similar numerals of reference indicate corresponding parts.

Referring to the drawings:

While my invention in its broad aspects, so far as concerns the hollow, live air actuated valve, its piston and the co-acting ports

and passages, is capable of adaptation to any portable pneumatic hammering implement, as a riveter, chipping hammer, rammer, rock drill or the like, I have shown it embodied in the present instance in a portable hand held rock drill, in which the forward end of the piston serves automatically to rotate the drill steel through the medium of a rifle nut and rifle flutes on the piston itself. I have confined the following description principally to the novel construction and mode of operation of the live air actuated, sleeve valve, its piston and the co-acting ports and passages, whereby the reciprocations of the valve and piston are effected, since the details of the assembly, and the construction of the forward portion of the implement, the drill holder, the water supplying devices, and the like, form no part of my present invention and can be variously arranged and organized, as will be evident to those skilled in the art.

1 designates my novel construction of hammer, the same comprising the cylinder 2, having the piston chamber 3, in which reciprocates the piston 4, having the forward extension 5 of reduced diameter and the rear cavity 6, indicated in dotted lines, which is of greater diameter than the forward extension 7 of the valve cap 8, which is provided with the valve block 9, containing ports and passages which co-act with the valve 10, seen detached in Fig. 5, the parts being held in assembled position by the outer head 11 and the bolts 12. The valve and piston are arranged in longitudinal alignment and the piston at its extreme rearward stroke is positioned within the valve as seen in Fig. 3, and the various parts are so designed and correlated that a very compact and efficient structure is produced. In Fig. 1, I have shown the position of the parts at the beginning of the rearward stroke of the piston 4, the valve 10 being at this period in its rearmost position and the piston being shown as starting on its rearward stroke. Live air is admitted to the pocket 13, by any suitable means, and passes through the screen 14, through the series of holes 15 into the annular groove 16, annular valve groove 17, into series of small holes 18, passage 19 and port 20 to the front shoulder 21 of the piston 4, whereupon the latter is impelled rearwardly from the position seen in Fig. 1 to the position seen in Fig. 3. While the piston 4 is moving rearwardly, the exhaust is leaving the rear end of the piston chamber 3 through the ports 22, 23, 24 and main exhaust opening 25. As the piston 4 starts rearwardly, from the position seen in Fig. 1 and during its initial rearward movement, the kickoff port 26, is covered. There is constant live air pressure in the passages 27 and 28 (see Fig. 2), the passage 27 communicating with the air sup-

plying pocket 13, and there will consequently be an accumulation of live air built up in the chamber 29 (see Figs. 1 and 2) through the port 30, whereby the valve 10 will be pressed rearwardly against its seat as seen in Figs. 1 and 2, during the initial rearward movement of the piston 4, during which period the forward end or valve face 31 is open or exposed to exhaust pressure only. While the valve faces 32 and 33 have some live air pressure on them due to leakage from the grooves 16 and 17, the live air pressure on the shoulder or valve face 34 obviously preponderates, since it does not depend upon leakage, but upon the direct constant live air supply introduced through the ports 27 and 28, and the valve is thus positively held in its rearward position, as seen in Fig. 1 against its seat for the proper period without fluttering. As the hammer or piston moves rearwardly from the position seen in Fig. 1 to the position seen in Fig. 3, it closes exhaust ports 22 and 23 (see Fig. 3) and the live air leakage around the rear valve face 33, will build up increasing pressure on the rear face of said piston and said rear valve face. While there is some cushioning action or compression which is always present, when a piston of any engine reaches either of its extreme positions during each stroke, this is of minor value in my construction, as compared to the accumulated live air leakage building up around the rear valve end or face 33. At that place in the rearward stroke, when pressure on the valve face or shoulder 34 is about balanced by combined pressure on the opposite valve faces, 32 and 33, the end of the hammer flute 35 (see Fig. 1) opens into the front of the piston chamber 3, air escaping therefrom to the front of the drill around the shank of the drill steel to the atmosphere. This lowers the air pressure in the front of the piston chamber 3, and when the piston uncovers port 26, the pressure on the valve face 34 is lowered, and owing to the preponderance of pressure upon the opposite valve faces or shoulders 32 and 33, the valve moves forwardly or trips or shifts to the position seen in Fig. 3. If the flutes 35 should be made not to uncover or were omitted entirely, it is apparent that the piston 4 would finally uncover the front exhaust port 36, as it nears its extreme rear position seen in Fig. 3, and effect the results as above explained. The parts are now in the position seen in Fig. 3, the piston 4 being in its rearward position and within the valve 10 and about to begin its striking or forward stroke, at which period the valve 10 is in its extreme forward position.

Live air now freely flows from groove 16, across the rear valve face 33, to the rear of the piston chamber 3, and forces the piston 4 forwardly. At this time the front

piston chamber is exhausting through the flutes 35 and 37, exhaust ports 36 and 25, and through passages 19 and 38, around the valve groove 17, groove 39 passages 24 and 25 to the atmosphere. The valve is now held in its forward position by the live air pressure on the rear face 33. As the piston continues on its down or forward stroke, the kick-off port 26 will be covered, live air pressure will 10 build up in the port 30, and the live air pocket 29, causing pressure on the face 34 of the valve thus tending to balance the pressure on the opposite face 33. When the piston uncovers the forward valve face 31 the 15 live air pressure in the rear of the piston chamber 3 will become effective on this face 31, and the sum of the pressures on the faces 31 and 34 will then overcome the pressure on the face 33 and the valve will be forced 20 or shift rearwardly from the positions seen in Fig. 3 to the position seen in Fig. 1 thus completing the cycle.

40 designates a direct live air port, seen in Fig. 3, which may be used as an alternative 25 if desired to lead live air directly to the rear valve face 33, to make the valve shift or trip quicker on the rear stroke of the hammer.

It will be apparent from the foregoing 30 that my novel valve is imperforate and is not weakened by the presence of holes or ports therein, and consequently it can be readily and cheaply manufactured and will be very durable in practical use.

It will further be apparent that my novel 35 arrangement of ports and passages, and by the provision of the chamber 6 in the piston, the piston is hollowed out for a great portion of its length thus reducing its weight and by causing the piston in 40 its rearmost stroke to enter the valve, as seen in Fig. 3, an extremely short and compact implement is produced, wherein the length overall and the weight will be reduced to a minimum. It will, of 45 course, be understood while as in all tools of this character, a cushion is formed to a greater or less extent at each end of the piston chamber 3, so that the piston will not impact upon the end walls of the piston 50 chamber, that my novel valve is not dependent upon, or actuated in either direction by, this cushion or compression of the air, but is actuated or shifted in both directions 55 solely by live air pressure, the valve being actuated rearwardly by live air pressure upon the front faces 31 and 34, and being actuated forwardly by live air pressure on 60 the faces 32 and 33, the live air pressure being augmented by the presence of the port 40 seen in Fig. 3.

It will further be evident that by this construction and arrangement of ports and 65 passages, a very accurate and instantaneous tripping or shifting of the valve into both its extreme positions is effected, and while

I have found in practice that my novel hammer will operate effectively with or without the live air port 40 seen in Fig. 3, it will operate somewhat more effectively when the said port 40 is employed. 70

It will be evident that in the manufacture and assembling of my novel valve mechanism and its adjuncts, the parts may be constructed and assembled somewhat differently from that shown, but I have found the construction shown to operate efficiently in practice under all conditions. While I have shown my novel valve mechanism in the present instance, as embodied in a relatively short stroke tool, it will be apparent that by the proper lengthening or modification of the necessary ports and passages, my novel valve mechanism can be employed with equal facility in long stroke pneumatic tools, such as riveters, where the hammering piston is 80 usually a plain cylindrical bolt and has a length of stroke considerably in excess of its own length. 85

Having thus described my invention what I claim as new and desire to secure by Letters Patent, is:— 90

1. In a device of the character stated, a cylinder, a piston chamber therein, a piston in said chamber having a forward extension of reduced diameter and provided with 95 flutes serving as exhaust passages, a valve box, a hollow imperforate sleeve valve therein, said piston being hollow at its rear end and passing through said valve on its rearward stroke, front and rear shoulders on said valve, an annular outer groove in said valve at the rear of said rear valve shoulder serving alternately as a live air inlet and an exhaust groove, and a head at the rear of said groove controlling the inlet to the front of 100 said piston chamber, means for admitting live air to said front and rear shoulders to shift said valve by live air, and a cap for 105 said valve box having a forward projection serving as a guide for the inner bore of said 110 valve.

2. In a device of the character stated, a cylinder, a piston chamber therein, a piston hollowed out in its rear, a valve box, a cap therefor having a forward projection of less 115 diameter than the cavity in said piston, an imperforate sleeve valve therein positioned around said forward extension and provided with front and rear shoulders said cap having a forward extension serving as a guide 120 for the inner bore of said valve, an outer groove in the rear of said rear shoulder serving alternately as a live air inlet and an exhaust groove, and a rear head controlling the inlet to the front of said piston chamber, means for admitting live air to said front and rear shoulders of said valve to shift the latter in opposite directions by live air only, and exhaust passages at the opposite ends of 125 said piston chamber. 130

3. In a device of the character stated, a cylinder, a piston chamber therein, a piston in said chamber having its forward end prolonged, of reduced diameter and provided with exhausting flutes on said forward end, and its rear end hollow, a valve box, a cap therefor having a hollow forward extension through which the piston moves in its rearward movement, said cap having also a larger forward extension serving as a guide for the inner bore of said valve, a hollow sleeve valve therein in line with said piston, the latter passing through said valve on its rearward stroke, front and rear pressure shoulders on said valve, a groove in the rear of said shoulders serving alternately as a live air inlet and an exhaust groove, and a head at the rear of said rear groove controlling the inlet to the front of said piston chamber, exhaust devices for the rear of said piston chamber, and means for admitting live air to said front and rear faces of said valve to shift it by live air.

4. In a device of the character stated, a cylinder, a piston chamber having a reduced forward extension provided with exhaust flutes therein, a hollow piston in said chamber, a valve box, a cap for the latter having a hollow forward extension adapted to enter the piston on the rearward movement of the latter, said cap also having a larger forward extension adapted to enter the inner bore of said valve when the latter is in its rearmost position, a hollow imperforate sleeve valve in said box, said piston passing through said valve on its rearward stroke, front and rear shoulders on said valve, an annular outer groove at the rear of said rear shoulder serving alternately as a live air inlet and an exhaust groove, and a head at the rear of said groove controlling the inlet to the front end of said piston chamber, an exhaust passage at the front of the piston chamber uncontrolled by said valve, another exhaust passage at the front of said chamber controlled by said valve, exhaust passages at the rear of said piston chamber controlled by both the piston and valve, a kick-off port alternately opened and closed by said piston, and live air passages leading to said front and rear valve shoulders, the live air passage leading to said front valve shoulder communicating with said kick-off port.

5. In a device of the character stated, a cylinder, a hollow piston chamber having a reduced forward extension provided with exhaust flutes therein, a piston in said chamber, a valve-box, a hollow imperforate sleeve valve therein, said piston passing through said valve on its rearward stroke, front and rear shoulders on said valve, an annular outer groove at the rear of said rear shoulder serving alternately as a live air inlet, and

an exhaust groove and a head at the rear of said groove controlling the inlet to the front of said piston chamber, a cap for said valve box having a hollow rearward extension serving as a guide for the inner bore of said valve when the latter is in its rearmost position, and means for admitting live air to said front and rear shoulders to shift said valve by live air only, the live air passage to the front of said valve having a communication with a kick-off port alternately opened and closed by said piston.

6. In a device of the character stated, a cylinder, a piston chamber therein, a piston in said chamber having its forward end prolonged and of reduced diameter and provided with exhausting flutes, and its rear end hollow, a valve box, a cap therefor having a hollow forward extension which closes said piston when the latter makes its rearward stroke, said cap also having a larger forward extension serving as a guide for the inner bore of said valve when the latter is in its extreme position, a hollow sleeve valve in line with said piston, the latter passing through said valve on its rearward stroke, a cap for said valve box having a forward projection of less diameter than the cavity in said piston, said valve surrounding said projection, front and rear pressure faces on said valve, a groove in the rear of said shoulder serving alternately as a live air inlet and an exhaust groove, and a head at the rear of said groove controlling the inlet to the front of said piston chamber, exhaust devices for the rear of said piston chamber, a kick off port alternately opened and closed by said piston and means for admitting live air to said front and rear faces of said valve to shift it by live air, the live air passage to the front valve shoulder communicating with said kickoff port.

7. In a device of the character stated, a valve comprising a cylindrical body portion having a passage of uniform diameter therethrough, front and rear pressure faces thereon, a groove in the rear of said rear face serving to control live air inlet and exhaust and a rear head serving to control the inlet to the forward end of the piston chamber, in combination with a piston adapted to enter said valve on its return stroke, a piston chamber for said piston, inlet and exhaust passages in said piston chamber controlled by said valve, live air inlet passages leading to said front and rear pressure faces, a kick off port alternately opened and closed by said piston and an auxiliary live air port for leading live air to the rear face of said valve, said live air passage leading to the front face of said valve communicating with said kick off.

LOUIS W. GREVE.
